US00D519739S

(12) **United States Design Patent** (10) **Patent No.:** **US D519,739 S**
(45) **Date of Patent:** **** May 2, 2006**

(54) **SURFACE PATTERN FOR A PAPER PRODUCT**

(75) Inventors: **Brian J. Schuh**, Appleton, WI (US);
John H. Dwiggins, Neenah, WI (US);
T. Phillips Oriaran, Appleton, WI (US); **Galyn A. Schulz**, Greenville, WI (US)

(73) Assignee: **Fort James Corporation**, Atlanta, GA (US)

(**) Term: **14 Years**

(21) Appl. No.: **29/230,962**

(22) Filed: **May 26, 2005**

(51) **LOC (8) Cl.** **05-06**

(52) **U.S. Cl.** **D5/37; D5/53; D5/57**

(58) **Field of Classification Search** ..... **D5/1-3, D5/5, 7-8, 11, 13-16, 19-20, 23-28, 30, D5/32, 35-37, 39, 43, 45, 47, 49-50, 52-66, D5/99; D2/749, 994; D6/582-583, 595-596, D6/598, 608, 603-606, 613, 616, 617, 619, D6/622; 428/17-18, 151, 154, 156, 171, 428/187, 198, 199, 540, 542.2, 542.6, 919, 428/904.4; D24/124, 125; D25/142, 152; 5/413 AM, 709; 162/134, 140, 231, 109; 156/148, 209; D7/396.4-5**

(57) **CLAIM**

The ornamental design for a surface pattern for a paper product, as shown and described.

DESCRIPTION

The sole FIGURE is a top plan view of a surface pattern for a paper product embodying our design.

The outer broken line boundaries depict the boundaries of the claimed design, and indicate that the design may continue in one or more directions, and are for illustrative purposes only, forming no part of the claimed design.

1 Claim, 1 Drawing Sheet
